UNITED STATES PATENT OFFICE.

ROBERT J. BURGIN, OF MARION, NORTH CAROLINA.

HYDROSTATIC OVERSHOT WATER-WHEEL.

1,255,510.

Specification of Letters Patent. Patented Feb. 5, 1918.

Application filed January 12, 1917. Serial No. 142,075.

To all whom it may concern:

Be it known that I, ROBERT J. BURGIN, a citizen of the United States of America, residing at Marion, in the county of McDowell 5 and State of North Carolina, have invented new and useful Improvements in Hydrostatic Overshot Water-Wheels, of which the following is a specification.

This invention relates to water wheels.

10 The primary object of the invention is the provision of a water wheel in which water is directed to the buckets in a manner to exert a hydrostatic pressure therein, each of the buckets acted upon remaining in a filled 15 condition so that the weight of the water is added to the force of the fall, thereby, increasing the power and effectiveness of the wheel.

Another object of the invention is to provide a wheel in which the water is fed to the buckets in a manner to keep each of them filled until they reach the exhaust, said filling means also forming a water seal for the bucket inlets to prevent emptying or partial emptying of the same before reaching 25 the predetermined point of discharge.

A further object of the invention is to provide a wheel in which the distributing chamber is removably and adjustably secured in position so that distributing chambers of various capacities may be used, the securing means being such as to permit of adjustment to take up wear and prevent leakage and waste of water.

30 With these and other objects in view the invention consists of the following novel combination, construction and arrangement of parts hereinafter more fully described and illustrated in the accompanying drawings; in which;

Figure 1 is a side elevation of the water wheel constructed in accordance with the invention;

Fig. 2 is an edge elevation thereof; 45 Fig. 3 is a central vertical sectional view of the same; and

Fig. 4 is a detailed view illustrating the manner of securing the distributing chambers to the periphery of the wheel.

50 Referring in detail to the drawings the invention consists of a frame, comprising a base 10, vertical supports 11 and connecting bars 12, within which a bearing 13 for a shaft 14 is secured. Mounted upon the shaft 55 14 is a hub 15 of the improved water wheel.

This wheel consists of the outer channel members 16 within which is formed the buckets 17, the same being connected to the hub 15 by means of spokes 18.

The buckets 17 entirely surround the periphery of the wheel and are adapted to receive water as a motive agent through the medium of the arcuate water distributing chamber 19. This chamber comprises an inner wall 20 and a channel portion 21. The inner wall 20 has secured along its edges arcuate shaped angle bars 22, the flanges of which are adapted to overlie the side flanges of the bucket 17 when the chamber 19 is in position. Formed in the said chamber are a plurality of openings 23 for establishing communication with the various buckets. In order to adjustably secure the said chamber 19 in position upon the periphery of the wheel, the frame is provided with transverse bars 24, preferably three in number, and these bars carry adjusting screws 25 which are swiveled or otherwise secured to the distributing chamber and by means of which the said chamber may be adjustably secured 80 in position. The manner of mounting this chamber provides for its removal and the substitution of a similar chamber of different capacity, should it be desired to regulate the power of the wheel by supplying less 85 water thereto. The buckets 17 are of angular shape, being widest at their entrance portion and each of the communicating openings 23 is provided with a transverse flange 26 formed by the cut out portions of the 90 openings for the purpose of more readily directing the water into the buckets.

Water is fed to the wheel through the distributing chamber 19, one end of the said chamber being provided with suitable inlet 95 and gate valve 27, by means of which the amount of water may be regulated. It will be seen from the above description and the accompanying drawings that the weight of the water is utilized as a motive force, in addition to the fall of the water and the leverage from the center of the wheel to the buckets, the diameter of the wheel of course regulating the leverage.

It is believed that the above when taken 105 in connection with the accompanying drawings is sufficient to enable persons skilled in the art to understand the construction, operation and advantages of the invention and that a further description is unnecessary.

Having described the invention, what I claim is:

1. The combination with a wheel rotatably mounted upon a support and provided with buckets opening around the periphery thereof, of a distributing chamber comprising an arcuate shaped receptacle having an inner wall adapted to be positioned to close the open ends of the buckets, said wall being provided with openings establishing communication between said buckets and chamber and transversely extending flanges provided by the cut out portions of the open-
- 5
- 15
- 20
- ings for directing the contents of the distributing chamber into the buckets.
2. The combination with a wheel, of a frame rotatably supporting said wheel, said frame including bars arranged transversely of said wheel, an arcuate distributing chamber and adjusting screws carried by said bars and engageable with said chamber for adjustably securing the latter against the periphery of the wheel.

In testimony whereof I affix my signature.

ROBERT J. BURGIN.
